UNITED STATES PATENT OFFICE.

HARRY GOLDFLAM, OF NEW YORK, N. Y.

DESIGN FOR A LADY'S BAG.

Application filed June 16, 1923. Serial No. 6,519. Term of patent 3½ years.

To all whom it may concern:

Be it known that I, HARRY GOLDFLAM, a citizen of the United States, residing in New York city, county and State of New York, and doing business at 465 West Broadway, in said city, have invented a new, original, and ornamental Design for a Lady's Bag, of which the following is a specification, reference being had to the accompanying drawings, forming part thereof.

I claim:

The ornamental design for a lady's bag as shown.

HARRY GOLDFLAM. [L.S.]
